ATTORNEY.

UNITED STATES PATENT OFFICE.

ROY K. BELDEN, OF SAN FRANCISCO, CALIFORNIA.

METHOD OF FILLING TEETH WITH PORCELAIN.

SPECIFICATION forming part of Letters Patent No. 738,517, dated September 8, 1903.

Application filed May 1, 1903. Serial No. 155,229. (No specimens.)

To all whom it may concern:

Be it known that I, ROY K. BELDEN, a citizen of the United States, residing at San Francisco, in the county of San Francisco and State 5 of California, have invented certain new and useful Improvements in Methods of Filling Teeth with Porcelain, of which the following is a specification.

My invention relates to an improved method 10 of making porcelain fillings for teeth, the object of my invention being to improve the method of making these fillings, so that they can be made with a much more accurate fit than heretofore.

15 Porcelain fillings are much superior to the more common gold fillings on account of their inconspicuousness as compared with the gold; but they are rarely used on account of the difficulty of making the fillings so as to exactly fit the cavity and of securing the fillings in place with accuracy, which is absolutely necessary for a successful porcelain filling.

25 The object of my invention is to provide a method by which great accuracy can be obtained in preparing the filling.

The steps of my improved method are illustrated in the accompanying drawings, in which—

30 Figure 1 is a sectional view showing the form of the cavity in dental cement. Fig. 2 is a sectional view showing the taking of the impression from the cement in a plastic composition. Fig. 3 is a sectional view showing the composition removed from the cement. Fig. 4 is a sectional view illustrating the step in which graphite is sprinkled upon the composition. Fig. 5 is a similar view illustrating the step in which copper is deposited upon 35 the graphite. Fig. 6 represents the copper plate from which the composition has been removed. Fig. 7 represents the copper plate reinforced by a backing of type-metal. Fig. 8 is a section showing the type-metal covered 40 with wax and the copper having a deposit of gold thereon. Fig. 9 is a view showing the gold matrix from which the copper has been dissolved. Fig. 19 shows the gold matrix filled with porcelain for baking. Fig. 11 shows 45 the porcelain filling from which the gold matrix has been dissolved.

In practicing my invention I first obtain

the form 1 of the cavity by pressing thereinto dental cement, which hardens very quickly. By means of the form thus obtained there is 55 then secured a duplicate 2 of the cavity in a composition of wax, paraffin, and graphite. This duplicate may be obtained either by pressing the composition down upon the form or melting the same thereupon, and this step 60 of obtaining the cavity in the composition is illustrated in Fig. 2. The dental cement is then removed, either by a suitable solvent or by mechanical means, leaving in the composition the exact form of the cavity of the 65 tooth, as shown in Fig. 3. The surface of this cavity and the surrounding surface are then brushed with graphite powder, (shown at 3 in Fig. 4.) Upon the graphite surface is then deposited by electrolysis a plate of copper, 70 (shown at 4 in Fig. 5.) The composition is then melted away, leaving the copper plate as shown in Fig. 6. The copper is then backed by type-metal 5, as shown in Fig. 7. Having first coated the metal with wax 6, gold 75 or platinum is deposited by electrolysis upon the copper plate, as illustrated in Fig. 8. The copper and type-metal are then dissolved, leaving the gold or platinum matrix 7, which is an exact duplicate of the cavity 80 in the tooth, as shown in Fig. 9. This matrix 7 is filled with powdered porcelain 8, as shown in Fig. 10, and is baked therein, and after it is baked the gold or platinum is dissolved by aqua regia, leaving the porcelain 85 filling 9, as shown in Fig. 11. The advantage of this method is that at no stage of the method is the accuracy of the reproduction of the filling, to correspond with the cavity, left to the skill of the operator, but it is determined by processes, such as electrolysis, 90 which insure perfect accuracy in the reproduction. It will also be observed by comparing the different steps that the cavity in the gold or platinum matrix is of precisely 95 the same size and shape as the original cavity in the tooth.

I claim—

1. A process of making porcelain fillings for teeth which consists of forming in a fusible material a copy of the cavity of the tooth, depositing by electrolysis a comparatively base metal therein to obtain a plate having thereon the form of the cavity, removing said

fusible material, depositing by electrolysis on said plate a precious metal as gold or platinum to form a matrix in said precious metal, dissolving the base metal from the 5 precious metal, to open the matrix, filling the matrix with porcelain powder, baking the porcelain, and removing the precious metal by aqua regia, substantially as described.

2. The process of making porcelain fillings 10 for teeth which consists in filling the cavity with cement to obtain a form, obtaining from said form a duplicate of the cavity in a fusible material, depositing by electrolysis a plate of base metal upon said fusible mate-

rial, removing the fusible material, depositing by electrolysis upon said plate a precious metal to obtain a matrix, dissolving the base metal to open the matrix, filling the matrix with porcelain powder, baking the powder, and removing the precious metal by aqua 15 regia, substantially as described.

In witness whereof I have hereunto set my hand in the presence of two subscribing witnesses.

ROY K. BELDEN.
